UNITED STATES PATENT OFFICE.

GOTTLOB HONOLD, OF STUTTGART, GERMANY.

SPARKING PLUG.

972,560.

Specification of Letters Patent. Patented Oct. 11, 1910.

Application filed November 5, 1907. Serial No. 400,830.

To all whom it may concern:

Be it known that I, GOTTLÖB HONOLD, engineer, a subject of the German Emperor, residing at 11 Hoppenlaustrasse, Stuttgart, 5 Germany, have invented certain new and useful Improvements in Sparking Plugs; and I do hereby declare the following to be a full, clear, and exact description of the invention, such as will enable others skilled in 10 the art to which it appertains to make and use the same.

This invention relates to a mode of fixing in place the insulating mass of a sparking plug, the object being to provide a gas-tight 15 joint around said mass, and is illustrated in the accompanying drawings wherein—

Figure 1 is an axial section through the plug before the insulating mass has been finally fixed in place, Fig. 2 is a like view 20 in which the final fixing has been effected and Fig. 3 is a like view of a modification.

In accordance with this invention, the insulating mass is constructed with a conical portion A which, when the parts are assembled, will be concentric with the cylindrical end B of the housing of the plug. Between this conical portion of the insulation and the cylindrical end of the plug housing or body, I fit a ring C having its inner and outer 25 faces converging downwardly whereby it will fit snugly between the insulation and the housing in smooth and intimate contact with both the said elements. After the ring 30 has been driven home, the end of the body or housing is bent over and down upon the ring, as shown at D in Fig. 2, to secure the ring in place.

Preferably the coned surface at A is sufficiently steep to produce a powerful wedge 40 action between the parts A and C; it is also advantageous that the ring C should be of such a diameter that it fits tightly into the cylinder B, so that the ring alone will hold the insulating mass accurately in place in 45 the plug before the operation of turning or pressing over the edge of the cylinder.

The ring C has the function of (1) keeping the insulating mass exactly central in the plug, (2) making the plug tight to gas 50 under pressure, (3) protecting the insulating mass from damage, since the ring receives the pressure exerted in turning over the edge of the cylinder. For fulfilling these functions the material of the ring 55 must be neither too hard nor too soft; as a

gas-tight packing the ring requires to be sufficiently deformable, while for exact centering and for receiving the mechanical pressure, the material of the ring should have a certain degree of resistance. Copper, red 60 brass or very soft iron are particularly suitable materials, although the application of other materials does not appear to be excluded. In order further to protect the insulating mass from damage a second packing ring E (Fig. 3) may be applied, which receives the pressure between the insulating mass and the plug in an axial direction. 65

The sparking plug constructed according to the invention presents the advantages 70 that it is simple and cheap, and that because of its simplicity it diminishes the possible sources of failure while it maintains its centering and its tightness as well as plugs of more complex construction do. 75

Having thus described my invention, what I claim and desire to secure by Letters Patent is:

1. In a sparking plug, the combination of a housing having a cylindrical interior, an insulating body loosely fitting therein and having an outwardly tapering conical portion, a ring having an outer diameter corresponding to the inner diameter of the housing and downwardly converging inner 85 and outer faces, fitting snugly in the wedge shaped annular space about the insulating body, and means to wedge the ring tightly into the said space.

2. In a sparking plug, the combination of 90 a housing having a cylindrical interior, an insulating body loosely fitting therein and having an outwardly tapering conical portion, a ring having an outer diameter corresponding to the inner diameter of the 95 housing and downwardly converging inner and outer faces, fitting snugly in the wedge shaped annular space about the insulating body, and means to permanently wedge the ring tightly into the said space. 100

3. In a sparking plug, the combination of a housing having a cylindrical interior, an insulating body loosely fitting therein and having an outwardly tapering conical portion, a ring having downwardly converging inner and outer faces, fitting snugly in the wedge shaped annular space about the insulating body, and terminating short of the bottom of the same to leave a free space 105 therein, and means to wedge the ring tightly 110

2

into contact with the outer face of the insulating body and the inner face of the housing.

4. In a sparking plug, the combination of
5 a housing having a cylindrical recess formed
therein, an insulating body loosely fitting
therein and having an outwardly tapering
conical flange above the bottom of the recess,
a heat-resisting gasket between the flange
10 and the bottom of the recess, a deformable
metallic ring having downwardly converging
inner and outer faces fitting as a wedge
snugly in the wedge shaped recess about the
flange and outside the periphery of the

gasket and terminating short of the bottom 15
of the recess, and nonremovable means to
force the ring downwardly into intimate
contact with the outer face of the insulating
body and the inner face of the housing
to center the former and to effect a gas 20
tight packing around the same.

In testimony whereof I have hereunto affixed my signature in the presence of two witnesses.

GOTTLOB HONOLD.
